UNITED STATES PATENT OFFICE.

EDGAR A. BECK, OF LOS ANGELES, CALIFORNIA.

ELECTRIC-ARC LAMP.

SPECIFICATION forming part of Letters Patent No. 670,658, dated March 26, 1901.

Application filed May 7, 1900. Serial No. 15,857. (No model.)

To all whom it may concern:

Be it known that I, EDGAR A. BECK, of the city of Los Angeles, in the county of Los Angeles, State of California, have invented certain new and useful Improvements in Inclosed Arc-Lamps, of which the following is a full, clear, and exact description or specification, reference being had to the annexed drawings and to the letters marked thereon.

My invention has partly for its object to enable the chamber which incloses the lower carbon and part of the upper carbon of inclosed arc-lamps to be always maintained with an air-tight joint at that part of the inclosing chamber where the upper edge of the glass shade or envelop is in contact with the cap constituting the upper part of the metallic frame by which the glass shade or envelop, the lower-carbon holder, and the upper-carbon guide or passage for the upper carbon into the inclosed arc-lamp chamber are maintained in their proper operative relationship. This object is effected by the construction of the metallic parts in such manner whereby certainty is insured that the several parts when assembled for operative use shall so fit together that the joining parts will bear so truly and squarely upon each other that leakage or admission of air at the aforesaid joint is prevented.

My invention has also for its object to enable the passage or hole through which the upper carbon passes into the arc-lamp chamber to make a practically air-tight joint around the upper carbon, while allowing the requisite freedom of motion of the upper carbon therein as the upper carbon is consumed, which joint is a mechanically-yielding joint and sensitive enough or sufficiently free to allow of the escape of gas generated in the carbon-inclosing chamber of the lamp, at the same time preventing the admission of air thereinto during the time the lamp is in action.

My invention has, furthermore, for its object to enable the glass shade or envelop and the lower carbon to be easily removed from the metallic framing and other parts of the inclosed arc-lamp chamber and to be readily replaced therein without separating or taking asunder the parts of the framing, this facility of removal of the glass shade or envelop be-

ing a resultant of the arrangement and construction of the framing and the connections of the same, as hereinafter described.

An advantage also resulting from my improved construction of inclosed arc-lamps is that I am enabled to adjust or trim the entire inclosed portions thereof when they are removed from the joint or coupling which connects them with the arc-lamp mechanism on the lighting-circuit. For example, when they are uncoupled or disconnected from the arc-lamp mechanism and taken into a house or apartment of an electric-lighting plant or station for the purpose of being cleaned and when the said parts are again put together after being cleaned I am enabled to ascertain by merely applying the inclosed chamber to the mouth and then blowing into the inclosure or inclosing chamber that the joints are tight before the lamp is replaced for being operated on the line, thus insuring that the lamps when replaced on the line are devoid of leaky joints and in perfect operative condition.

On the annexed drawings, Figure 1 is a front elevation of my improved inclosed arc-lamp. Fig. 2 is a corresponding elevation of the same, but with the upper and lower portions of the glass chamber or envelop broken away in order to show the construction of the upper and lower caps of the lamp and the packing through which the upper carbon passes. Fig. 2^a is a side elevation of the said lamp. Fig. 2^b is a plan of the upper part of the said lamp. Fig. 3 is an inverted plan of the upper cap of my improved arc-lamp. Fig. 4 is a transverse section of the portions of the upper cap on a larger scale than shown at Figs. 1, 2, and 3, this Fig. 4 showing also the packing for the upper carbon. Fig. 5 is a plan of the packing for the upper carbon corresponding to Fig. 4, but with the upper cap of the packing-chamber removed in order to show the construction of the packing itself within said chamber. Fig. 6 is an inverted plan of the central packing-ring, corresponding to Figs. 4 and 5. Fig. 7 is an outside elevation of one upper and one under segment of the central packing-ring, showing the relationship of the upper and under segments to each other, the rest of the ring being indicated in dotted lines. Fig. 8 is a plan corresponding to Fig. 7. Fig.

9 is an inside elevation of one of the upper and one of the under segments of the central packing-ring, showing the relationship of the upper and under segments thereof to each other. Fig. 10 is an inverted plan of Fig. 9.

In Figs. 1, 2, 2^a, and 3 the glass shade or envelop of the lamp is marked A. The upper cap-piece is marked B, and the lower cap is marked C. The upper cap B has attached to it the plate D, to which the rods E are rigidly fastened, the lower ends of these rods E being provided with thumb and finger nuts F, which are attached to fit on the screw-threaded lower terminals of the rods E E. Upon the lower ends of the rods E E the angularly-bent transverse bar G is carried, having holes at the ends thereof passing over the studs e e, projecting inwardly from the blocks f f, which are formed with holes, so as to slide freely upon the rods E E, so that by tightening the nuts F F the spiral springs g g, carried upon the rods E E, are compressed, whereby the upper and lower caps B and C, respectively, are pressed with any required degree of elastic pressure upon the upper and lower edges of the glass shade or envelop A A. The upper and lower caps B and C are provided with a layer of asbestos or other packing H and H', respectively, at the parts where these caps bear against or upon the edges of the glass shade or envelop, as shown at Figs. 2, 3, and 4.

By reason of the rods E E and the upper cap B being permanently and rigidly connected together in placing the glass shade or envelop A into its place in the lamp-framing and tightening all the parts together by means of the nuts F F all the parts constituting the inclosing chamber are held together with the required degree of tension or elastic pressure produced by the intervention of the springs g g, and the upper cap B is insured of bearing squarely upon the upper edge of the chamber or envelop A. The lower cap C is also presssd elastically and squarely up against the lower edge of the glass chamber of the shade or envelop A by means of the springs g g and the adjustable central screw I, while the arrangement is such as to admit of the glass shade or chamber A being readily removed from the framing of the inclosed arc-lamp by merely pulling down the bar G G by applying the thumb and finger to the head of the thumb-screw I, which enables the bar G G to be swung on its studs e e into the position shown at Fig. 2^a, in which position the shade or envelop A and the lower carbon are set free from the other parts of the inclosed arc-lamp. By means of this arrangement whereby the rods E E are rigidly connected to the plate D and the upper cap A A, and whereby, too, the under cap C is pressed upward by means of the adjustable transverse rod G, screw-nuts F F, springs g g, and screw I the certainty is insured that the joints at the upper and lower ends of the glass chamber or envelop A are at all times air-tight without any great care being exer-

cised on the part of the attendant or trimmer of the inclosed arc-lamps, and in practice I find that by means of this construction of the hereinbefore-described parts of an inclosed arc-lamp leaky joints at the upper and lower ends of the glass envelop or chamber, and especially at the upper end of the glass envelop or chamber, are entirely got rid of.

The lower cap C is provided with set-screws J for adjusting the relationship of the cap with the lower edge of the envelop A.

The packing surrounding the upper carbon K consists of two or more superposed segmental rings. In the drawings two such rings are shown, the segments constituting the upper of which rings are marked L, L', L'', and L''' in Fig. 5, and the segments constituting the lower of which rings are marked M, M', M'', and M''' in Fig. 6. The upper ring, composed of the segments L, L', L'', and L''', has a recess formed in its under side, as shown at Fig. 6, whereinto the segments constituting the lower ring M, M', M'', and M''' fit, and the transverse joints of the two rings L, L', L'', and L''' and M M' M'' M'''—namely, the joints marked a a a a and b b b b in Figs. 5 and 6, respectively—are so arranged that the transverse joints b b b b break joint with the transverse joints a a a a, the several parts constituting these two segmental rings and their joints being sufficiently well fitted together as to enable them to bear with sufficient closeness upon each other to practically prevent a “blow-through” between or among the several joints, the “break-joint” of the parts materially aiding to produce the close fitting or tightness of said joints.

By reference to Figs. 7, 8, 9, and 10 the construction of each segment constituting the packing-ring will be easily understood, and it is here explained that in order to maintain the several segments in the requisite break-jointed positions when the ring is in its place and operating in the inclosed arc-lamp one of the lower segments and upper segments are held together by means of a stop-pin, as shown at c, Figs. 5, 6, 8, and 10 of the drawings.

The hole N in the center of the packing-ring, Figs. 5, 6, 8, and 10, is of the size requisite to allow the upper carbon K to pass therethrough.

As shown at Figs. 4 and 5, the upper exterior packing-ring, composed of the segments L, L', L'', and L''', is preferably formed slightly tapered at its exterior, and in the annular inclosure O, around about the packing-ring, a number of metallic weights, preferably in the form or shape of spheres P, are contained. The lower part of the annular inclosure O is slightly inclined downward toward the segments of the packing-ring L L' L'''', so that the tendency of the metallic weights P P P is to press by reason of their spherical shape or form upon the exterior of the packing-ring, and thereby to press the segments of the said packing-ring evenly and concentrically all around the upper carbon, by

which arrangement gas generated within the inclosed chamber of the lamp to which pressure is or may be imparted by reason of heat produced within the lamp is allowed to escape 5 through the yielding of the segments to such gas-pressure, while air from without is prevented from entering into the lamp when the lamp is in operation. The segmental packing-rings L L' L'' and M M' M'' M'', together 10 with the weights P P P, are maintained within the inclosure O by means of the cap Q, which is screwed upon the inclosure O, as shown at Figs. 2 and 4. The lower part of the chamber constituting the inclosure O is provided 15 with a tubular projection R, Figs. 2 and 4, upon which the screwed nut S is carried, the object of which is not only to fasten the inclosure O and the packing within it to the upper cap B and plate D of the lamp, but 20 also to enable the ordinary coupling-inclosure T, the plate U, and the rods V V of the arc-lamp mechanism to be insulated from the cap-piece B and the upper carbon. The ring T, which is of a kind commonly used, makes electrical connection with the plate D and thence 25 through the rods E E, bar G, and screw I with the lower carbon W.

Having now described the nature of my said invention and the best system, mode, or manner I am at present acquainted with for carrying the same into practical effect, I desire to observe, in conclusion, that what I consider to be novel and original, and therefore claim as the invention to be secured to me by Letters Patent, is as follows:

1. The inclosed arc-lamp wherein the joint of the upper end of the glass envelop with the cap is maintained by an extension of the cap-plate at either side, each such extension having a vertical rod rigidly attached thereto, so that the cap and these rods always maintain a constant relationship of immovability with respect to each other, while the cap at the lower end of the glass shade is carried and 45 pressed vertically upward by a transverse bar, elastically suspended by springs and adjusting-nuts upon said rods, said transverse bar having a central adjustable projection bearing upward against the bottom cap of the 50 lamp, and said bar being carried upon pivots or studs forming part of a sliding block on each of the rods all constructed and operating substantially as hereinbefore described.

2. That part of an inclosed arc-lamp consisting of the upper cap and plate insulated from the upper carbon, the vertical rods rigidly attached to the upper plate, the sliding blocks with pivots at the lower part of these rods, the transverse bar movable on the pivots of these 60 sliding blocks with pivots, the springs for forcing the sliding blocks with pivots and transverse bar upward for maintaining the shade or envelop air-tight against the upper and lower seats of the shade or envelop, the screw

nuts and threads on the lower parts of the rods 65 and the cap for closing the bottom of the shade or envelop, all operating together substantially as hereinbefore set forth.

3. In an inclosed arc-lamp the combination of the glass shade, the cap at the top of the 70 glass shade the rods rigidly attached to this cap, the pivoted transverse bar, the pivotal sliding blocks, the cap at the lower end of the glass shade, the projecting screw at the center of the transverse bar bearing against the 75 center of the lower cap, the nuts on the screw-threaded lower ends of the rods, the spiral springs on said rods, the glass shade or envelop, all substantially as hereinbefore described. 80

4. In an inclosed arc-lamp the combination of the glass shade, the cap at the top of the glass shade, the vertical rods rigidly attached to this cap, the pivoted transverse bar, the pivotal sliding blocks, the cap at the lower 85 end of the glass shade, the projecting screw at the center of the pivoted transverse bar bearing against the center of the lower cap, the nuts and the spiral springs on the screw-threaded lower ends of the vertical rods, the 90 glass shade or envelop, all operating to produce air-tight joints at the upper and lower ends of the glass shade and the air-tight packing carried by the upper cap and around the upper carbon, and the insulation, all constructed and operating substantially as hereinbefore described. 95

5. The packing for the upper carbon consisting of a central ring portion constructed of segments in layers breaking joint with each 100 other and pressed peripherally against the upper carbon by a series of weights contained within a casing and arranged so that the weights constantly press peripherally against the segmental ring, the joints of the segments 105 of one ring breaking joint with the segments of the next ring, substantially as hereinbefore described.

6. The casing or inclosure containing the segmental rings, the segmental rings, the segmental joints of one ring breaking joint with the segmental joints of another ring, the weights within said casing or inclosure pressed against the segmental ring, the screw-threaded tubular stem at the under side of said casing, or inclosure, the nut thereon and the insulating-rings for said packing and the upper carbon from the lower carbon of an inclosed arc-lamp, substantially as hereinbefore described. 115

In testimony whereof I have hereunto set my hand and seal, this 9th day of April, in the year of our Lord 1900, in the presence of two subscribing witnesses.

EDGAR A. BECK. [L. S.]
